AUTOMATIC MOTOR FUEL CONTROL

Frederick S. Gleockler, Albert Gleockler, and
Frederick M. Gleockler, Camden County, N. J.

Application April 14, 1936, Serial No. 74,364

8 Claims. (Cl. 123—196)

This invention relates to means adapted to operate automatically to cut off the flow or supply of fuel to an internal combustion engine in the event of oil failure within the engine such as 5 stoppage of the oil circulating system, or the absence of a sufficient quantity of the oil for efficient operation.

It is further aimed to provide a novel structure wherein the result is accomplished by means primarily under control of the pressure of the oil 10 or lubricant.

It is further aimed to provide a novel structure of a valve particularly adapted for use in the new organization, the same having ground seats and 15 being constructed generally to prevent undesired admixture or interflow of fuel and oil.

The more specific objects and advantages will 20 become apparent from a consideration of the description following taken in connection with accompanying drawings illustrating an operative embodiment.

In said drawings:—

Figure 1 is a view in side elevation illustrating our improvements;

Figure 2 is a view on an enlarged scale, primarily through the novel valve employed, the parts being in normal position wherein fuel flows to the engine;

Figure 3 is a view similar to Figure 2 but showing the fuel to the engine cut off, as in case of oil failure;

Figure 4 is a horizontal sectional view taken on the line 4—4 of Figure 3;

Figure 5 is a vertical sectional view taken on the line 5—5 of Figure 3;

Figure 6 is a view in elevation showing the sections of the valve body detached.

Figure 7 is a fragmentary vertical sectional view through a modified form.

Referring specifically to the drawings wherein like reference characters designate like or similar parts, 10 illustrates an internal combustion engine having a fuel line 11 leading from a fuel supply tank 12, through a vacuum tank 13, to a carburetor 14, communicating in the usual way with the intake manifold 15 of said internal combustion engine.

Said engine has an endless conduit 16 in communication with the crank case and through 50 which the lubricating oil of such crank case for the engine passes, being circulated under pressure by a pump 17 suitably driven from the engine. A branch pipe 18 extends from the lubricant pipe 16.

55 A vertical cylindrical casing 19 has bosses 20

and 21 at opposite sides thereof to which the adjacent portions of the pipe forming the fuel line 11 are connected by means of screw-threaded nipples or the like 22 and 23, said bosses having bores or ports 24 therethrough communicating 5 with the interior of the casing.

Said casing 19 has a cap 26 screwed tightly thereto with a gasket 27 interposed and a branch pipe or conduit 28 is connected to the cap by means of a nipple 29 screw-threaded thereto, and 10 which branch is also connected to a coupling 30 connected in the line 11 between the vacuum tank and the casing 19.

Screw-threaded at 31 to the lower end of the casing 19 is a cap 32 to which the branch 18 of 15 the lubricant circuit 16 is connected as by means of a screw-threaded nipple 33, the cap 32 having a passage communicating with said nipple and with the interior of the casing.

Said casing 19 has an interior annular enlargement at 35, below the ports 24 and 25, which has oppositely beveled shoulders 36 and 37, at the upper and lower ends thereof. A valve body 38, detailed in Figure 6, is slidable within the casing 19, and it consists of upper and lower sections 39 25 and 40, detachably connected together by means of a screw-threaded shank or stud 41 on the section 39 engaging a screw-threaded recess 42 in the section 40. Said sections respectively have beveled shoulders at 43 and 44, a greater distance apart than the shoulders 36 and 37, and 30 respectively adapted to engage the same in the closed and open condition or position of the valve to cut off or permit the passage of a fuel through the line 11 to the carburetor.

35 Since it is essential that a fuel and oil should not admix or interflow or one flow into the line of the other, the valve seats 36, 37, 43, and 44 are preferably ground. It will be noted that the section 40 has a stem 45 of substantially the same diameter as the bore of the enlargement 35 and which stem is preferably annularly grooved as at 46 to facilitate the flow of fuel in the line 11.

A flexible packing cup 47 is fastened to the top of the valve section 39 by means of a screw 48 45 and disc 49, with an expansive spring 50 in engagement with the latter and with the cap 26. A chamber or space 51 is provided in the casing above the cup which is filled with fuel admitted through the branch 28 so that the valve will be 50 subject to the weight of such fuel as well as any pressure thereon.

At the lower end of the valve section 40, a flexible packing cup 52 is secured by means of a screw 53 and a disc 54, a space or chamber 55 re- 55

maining below the same in the casing 19 designed to be filled with lubricant through the branch 18 and to be subject to the pressure of such lubricant normally maintains the valve body in the 5 position shown in Figure 2, permitting the flow of fuel through the line 11 to the carburetor or engine.

It will be noted that a screw 56 is threaded in the cap 32. Such screw 56 is adapted to be turned 10 against the lower end of the valve body to raise it from a closed position as in Figure 3 to the open position as in Figure 2, when starting the internal combustion engine or if the device has cut off the fuel supply, and it is estimated that 15 it will not be injurious to operate the engine, knowing the lubricating system would be impaired.

It will be understood that normally the valve body is in the position shown in Figure 2, the 20 passage 46 aligned with the ports 24 and 25 permitting the flow of fuel to the engine, the valve body under such conditions being subject to the weight and pressure of the fuel from above and subject to the pressure of the oil from below, the 25 pressure of the latter overcoming that of the fuel and the spring 50 so that under normal conditions the valve remains in the open position of Figure 2, with the seat 44 and 37 intimately engaging to prevent any interflow or admixture of fuel and 30 oil. In the event the oil circuit 16 should become clogged, the oil level or quantity becomes greatly abnormal, the pressure in the circuit will be affected or impaired and the pressure will not be sufficient to maintain the valve body raised 35 as in Figure 2 and hence it will fall by gravity aided by the weight and pressure of the fuel and tension of the spring from above, moving the valve seat 43 into engagement with the valve seat 36 as shown in Figure 3, completely cutting off 40 the supply of fuel through the chamber or casing 19.

It is clear that a lock nut 60 may be provided on the bolt 56 if desired.

While the screw 56 is desirable for use on 45 trucks, and may even be used on passenger vehicles, yet it is preferably desired to provide means for use on passenger cars, and is practically necessary when driven by women, as it will provide a means which will accomplish the 50 same function as the set screw 56 and which may be operated from the instrument board of the vehicle. A construction accomplishing this end is disclosed in Figure 7. In this form, the cap 32' which is the equivalent of that at 32 has a rod or 55 plunger 61 slidably mounted centrally thereof. A nipple or guide sleeve 62 is threaded to the cap 32' and the plunger 61 has an enlargement 63 operating in such tube, its upward movement being limited by engagement with an inwardly extending flange 64 and its lower movement being limited by engagement with a shoulder 65 of the cap 32'. Below the shoulder 65 packing 66 is provided about the plunger 61, the same being held in place by a gland 67 screwed into the cap 60 65 32'. A pin or abutment 68 is provided on the plunger and an expansive coil spring 69 surrounds the plunger, abutting the gland at one end and the pin 68 at the other end. Thus the plunger is urged to and maintained in its lowermost position. A lever 70 is pivoted at 70' to said cap 32' and it has an offset portion 71 engageable with the lower end of the plunger 61. A draw rod or the equivalent 72 is connected to the lower end of the lever 70.

75 As a result of the construction described, in

the event it is desired to raise the valve body, for the same purposes that it is raised by the screw 56, element 72 is pulled from the instrument board or the like thereby causing the lever 70 at portion 71 to engage and raise the plunger 61 the 5 latter contacting with the valve body and raising it to the position shown in Figure 7 so that the fuel may pass through the fuel line. In this position, the rod 72 may be held by hand as long as desired or suitable means may be provided to 10 latch or secure it in such position. The spring 50 may be dispensed with when the device is used with a forced-feed fuel system as the pressure of the fuel is in such instance the only requisite to operation of closing the passage for the fuel 15 to the carburetor.

We claim as our invention:—

1. In combination with the fuel supply line and pressure-oil circulating line of an internal combustion engine, a casing connected to the fuel 20 supply line, branches leading from the fuel supply line and pressure oil circulating line to the upper and lower ends of the casing respectively, a vertically movable valve body in the casing subject to the pressure of the oil and having a passageway therein between its upper and lower ends to maintain the fuel supply line open, said valve body being also subject to the weight and pressure of the fuel so that in the event of oil-failure, said valve body will lower to cut off the flow of 30 fuel in the fuel supply line, said casing having interiorly thereof spaced apart shoulders, and said valve body having shoulders spaced apart a greater distance than the first mentioned shoulders and engageable therewith. 35

2. In combination with the fuel supply line and pressure-oil circulating line of an internal combustion engine, a casing connected to the fuel supply line, branches leading from the fuel supply line and pressure oil circulating line to the 40 upper and lower ends of the casing respectively, a vertically movable valve body in the casing subject to the pressure of the oil and having a passageway therein between its upper and lower ends to maintain the fuel supply line open, said valve body being also subject to the weight and pressure of the fuel so that in the event of oil-failure, said valve body will lower to cut off the flow of fuel in the fuel supply line, said casing having interiorly thereof spaced apart shoulders, 45 and said valve body having shoulders spaced apart a greater distance than the first mentioned shoulders and engageable therewith, spring means within the casing urging downward movement of the valve body, and means carried by the casing 50 operable to move the valve body to open position. 55

3. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on opposite ends 60 of said casing forming inlets adapted to communicate with a fuel supply line and an oil supply line. 65

4. A device of the class described having a vertical casing provided with inlet and outlet ports 70 intermediate the ends thereof, said casing having interior spaced apart shoulders, a vertically movable valve body within the casing having a reduced portion intermediate its ends and provided with shoulders spaced a greater distance 75

- apart than the first mentioned valve seats and adapted to engage the latter, and caps on opposite ends of said casing forming inlets adapted to communicate with a fuel supply line and an oil supply line, said casing having an integral enlargement providing first mentioned shoulders, and an element operable through one of said caps to positively move and maintain the valve body in an open position.
5. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said valve body comprising sections detachably secured together.
10. 6. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on opposite ends of said casing forming inlets adapted to communicate with a fuel supply line and an oil supply line, said shoulders being ground, packing cups at the outer ends of the movable valve body, and an expansive spring engaging one of the caps and the uppermost packing cup, said valve body being in sections, one of said sections having a screw element detachably engaged in the other, said reduced portion having a channel about the same.
15. 8. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said casing having an integral enlargement providing first mentioned shoulders, and an element operable through one of said caps operable to positively move and maintain the valve body in an open position, comprising a plunger, spring means urging said plunger to lowermost position, said plunger having an enlargement, means in the path of movement of the enlargement to limit the upper and lower movement of the plunger, a lever pivoted on the adjacent cap, and means operable to move said lever against the plunger to raise it.
20. 7. A device of the class described having a vertical casing provided with inlet and outlet ports intermediate the ends thereof, said casing having interior spaced apart shoulders, a vertically mov-
- able valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said shoulders being ground, packing cups at the outer ends of the movable valve body, and an expansive spring engaging one of the caps and the uppermost packing cup.
25. 9. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said casing having an integral enlargement providing first mentioned shoulders, and an element operable through one of said caps operable to positively move and maintain the valve body in an open position, comprising a plunger, spring means urging said plunger to lowermost position, said plunger having an enlargement, means in the path of movement of the enlargement to limit the upper and lower movement of the plunger, a lever pivoted on the adjacent cap, and means operable to move said lever against the plunger to raise it.
30. 10. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said casing having an integral enlargement providing first mentioned shoulders, and an element operable through one of said caps operable to positively move and maintain the valve body in an open position, comprising a plunger, spring means urging said plunger to lowermost position, said plunger having an enlargement, means in the path of movement of the enlargement to limit the upper and lower movement of the plunger, a lever pivoted on the adjacent cap, and means operable to move said lever against the plunger to raise it.
35. 11. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said casing having an integral enlargement providing first mentioned shoulders, and an element operable through one of said caps operable to positively move and maintain the valve body in an open position, comprising a plunger, spring means urging said plunger to lowermost position, said plunger having an enlargement, means in the path of movement of the enlargement to limit the upper and lower movement of the plunger, a lever pivoted on the adjacent cap, and means operable to move said lever against the plunger to raise it.
40. 12. A device of the class described having a vertical casing provided with inlet and outlet ports intermediate the ends thereof, said casing having interior spaced apart shoulders, a vertically movable valve body within the casing having a reduced portion intermediate its ends and provided with shoulders spaced a greater distance apart than the first mentioned shoulders and adapted to engage the latter, and caps on the opposite ends of said casing forming inlets adapted to communicate with a fuel supply line and an oil supply line, said casing having an integral enlargement providing first mentioned shoulders, and an element operable through one of said caps operable to positively move and maintain the valve body in an open position, comprising a plunger, spring means urging said plunger to lowermost position, said plunger having an enlargement, means in the path of movement of the enlargement to limit the upper and lower movement of the plunger, a lever pivoted on the adjacent cap, and means operable to move said lever against the plunger to raise it.
